(57) CLAIM

The ornamental design for a serving container, as shown and described.

DESCRIPTION

FIG. 1 is a top perspective view of a serving container, according to an embodiment of the invention;

FIG. 2 is a front elevation view of the serving container of FIG. 1;

FIG. 3 is a rear elevation view of the serving container of FIG. 1;

FIG. 4 is a top plan view of the serving container of FIG. 1; FIG. 5 is a bottom plan view of the serving container of FIG. 1;

FIG. 6 is a left-side elevation view of the serving container of FIG. 1; and,

FIG. 7 is a right-side elevation enlarged partial view of the serving container of FIG. 1.

The broken lines depict portions of the kitchen serving set that form no part of the claimed design.

1 Claim, 4 Drawing Sheets
